(57) **CLAIM**

The ornamental design for a surface cleaning device, as shown and described.

DESCRIPTION

FIG. 1 is a front perspective view of a surface cleaning device.

FIG. 2 is a front view of the surface cleaning device of FIG. 1, the back being a mirror image.

FIG. 3 is a top view of the surface cleaning device of FIG. 1, the bottom being a mirror image.

FIG. 4 is a side view of the surface cleaning device of FIG. 1, the opposite side being a mirror image.

FIG. 5 is a front perspective view of the surface cleaning device of FIG. 1 with top and bottom caps being shown removed from a housing of the surface cleaning device.

FIG. 6 is a front perspective view of the surface cleaning device of FIG. 1 with the top and bottom caps hidden.

FIG. 7 is a front view of the surface cleaning device of FIG. 1 with the top and bottom caps hidden, the back being a mirror image.

FIG. 8 is a top view of the surface cleaning device of FIG. 1 with the top cap hidden.

FIG. 9 is a bottom view of the surface cleaning device of FIG. 1 with the bottom cap hidden; and,

FIG. 10 is a side view of the surface cleaning device of FIG. 1 with the top and bottom caps hidden, the opposite side being a mirror image.

The broken lines in the drawings illustrate portions of the surface cleaning device which form no part of the claimed design.

1 Claim, 9 Drawing Sheets

OTHER PUBLICATIONS

Photographs of product by Monster Cable Products, Inc., "Clean Touch." A printout of a webpage in which the Clean Touch product was offered for sale is also included. The printout indicates that the product was first offered for sale on Apr. 15, 2011; however, Applicant makes no representations as to the accuracy of this date or if the product has changed since that date. The printout was retrieved from Amazon.com on Apr. 2, 2015. The "publication date" of this reference is not readily available. Applicant requests that the Examiner review the reference as prior art. Applicant reserves the right to disqualify the reference as prior art if needed.
